HENRY C. PEARSON, OF PASADENA, CALIFORNIA

BALL AND PROJECTOR THEREFOR

Application filed April 1, 1929. Serial No. 351,648.

My invention relates to improvements in the art of play balls, designed to provide an article of manufacture deviating from the common unbroken spherical ball body used for play, and which can be manufactured of any suitable substance other than rubber as well.

The principal object of my invention is to provide a play ball that, unlike the ordinary ball is not thrown or struck at, but which depends for locomotion entirely on a thrust or effort of the player to roll it forward, suitable means for readily accomplishing this being provided as herein shown, the combination furnishing a most unique method for acquiring wholesome exercise, as well as being adaptable to the formation of a game providing healthful pastime for both sexes—old or young, the diameter of the ball being regulated strictly by the purpose of its use.

At present there are few lawn games of easy and practical application, and with few exceptions, cement or other specially prepared courts or grounds are necessary. One object in this invention is to provide the means for a game that can be played on any lawn or yard or any suitable place without special preparation or change. Furthermore to provide such a means that anyone may play without undue strain or effort and, what is of utmost importance, without the necessity of stooping common to practically every outdoor game.

Ball games particularly for lawns have been of two major types, first, where the ball is rolled by hitting it, as in croquet, and second, where it is released by an underhand throw similar to a low long swing of the arm as in bowling. In my invention neither of these methods is used, the ball rests on the ground and is rolled toward the goal by means of a pusher that gives it a rotary motion from the start. It is not a blow, nor a throw or a sliding force, but a continuous rolling motion from start to finish, and exceedingly effective with very little effort.

I attain this object by means of the combination illustrated in the accompanying drawings, in which:

Figure 1 is a ball in elevation, and having a circumferential groove or recess, and shows a form of transverse axle.

Figure 2 is an elevation on line X2—X2 of Figure 1, showing the axis, through the body 55 of the ball.

Figure 3 is a side elevation showing one form of pushing rod, one end of which is forked to straddle the outwardly extending axle ends.

Figure 4 is a mid-sectional elevation showing another form of pushing rod, the forked end of which straddles the circumferential groove of the ball body.

Figure 5 shows a further modified form of 65 push rod, a turned-under member or hook being incorporated in combination with the forked end, and serves to provide an adequate means for lifting the ball from the surface on which it rests, and, if desired, provides also a ready means for pulling the ball. 70

Figure 6 is a plan view of a solid ball indicating both the appearance and position of the engaging push rod of the type shown in Figures 3 and 5.

Similar numerals refer to similar parts throughout the several views.

1 indicates a ball having convex sides 2 and 3, 4 indicates a transverse axle that extends beyond said sides 2 and 3 and which terminate in flanged ends 5. Disposed on the circumferential body of the ball and intermediate said convex sides is a recess or groove 6.

As a means of rotating the ball I provide a pushing rod 7 having a handle 8, and as indicated in Figure 6, a forked end 9 having members 11 and 12 which in one form of pushing rod terminate in forks 13 and 14 adapted to straddle the axle 4 as is shown in Figures 3 and 6.

As a modification of the pushing rod, said members 11 and 12 are provided with hooks 15 and 16 as shown in Figure 5, and for all practical purposes, a pushing rod may be employed of either type, that is, with or without the hooks.

Referring now to Figure 4, a further modification of the pushing rod is employed when the player elects to cause the ball to roll by means of contact with the circumferential

groove in place of the axle ends, the handle 8 terminating into a fork comprising members 10 adapted to engage said groove.

As a practical article of manufacture, the ball can be produced either as a solid or hollow object and while the drawing shows the ball with the axle extending beyond its sides, it is obvious that it can be made with or without an axle or in combination as shown, either type of ball as may be preferable, serving the purpose alike.

As a means for formulating a game, my device offers a practical and most efficient combination. It will be found equally interesting for indoor games as for out-door games; requires similar skill for propelling the ball in a given direction as in croquet and billiards, the rolling or forward movement of the ball being as practical as it is new.

I am aware that slight modifications may from time to time be made in the details of construction without departing, however, from the scope of the present invention as herein set forth, and as defined in the claims which are appended hereto. Hence, I do not limit my present invention to the exact description of construction herein disclosed, but what I do claim as new and novel is:

1. The combination of a ball having means projecting therefrom for engagement by a propelling member, the latter consisting of a grip member and hook means, said hook means having a part opening forwardly for engagement with the first mentioned means for pushing the ball and a part opening rearwardly for engagement with the same means for drawing the ball backwardly.

2. In combination with a ball having means projecting therefrom adapted for engagement with an engaging member, an engaging member whereby said ball is releasably held under control, said engaging member comprising a pushing rod embodying a hand grip and a plurality of hook members two of which extend outwardly from said rod and by means of which the projections on said ball may be engaged and the ball forced forwardly and the other hook members extending rearwardly whereby said projections may be engaged to draw the ball backwardly.

HENRY C. PEARSON.
